US00D826735S

(12) United States Design Patent (10) Patent No.: US D826,735 S
O'Neill (45) Date of Patent: * Aug. 28, 2018

(54) PACKAGING

- (71) Applicant: SUGARFINA, INC., Inglewood, CA (US)
(72) Inventor: Rosie Colleen O'Neill, Inglewood, CA (US)
(73) Assignee: SUGARFINA, INC., El Segundo, CA (US)

() Term: 15 Years

(21) Appl. No.: 29/608,655

(22) Filed: Jun. 23, 2017

(57) CLAIM

The ornamental design for a packaging, as shown and described.

DESCRIPTION

FIG. 1 is an exploded perspective view of a packaging showing my new design;

FIG. 2 is a perspective view thereof, shown without the insert and packaging tray for clarity of illustration;

FIG. 3 is a front view thereof;

FIG. 4 is a rear view thereof;

FIG. 5 is a top view thereof; and,

FIG. 6 is a side view thereof.

The broken lines shown represent unclaimed subject matter and form no part of the claimed design. The shade lines shown represent surface shading and not surface ornamentation.

1 Claim, 4 Drawing Sheets
